UNITED STATES PATENT OFFICE.

SAMUEL K. SWEITZER, OF NEW FREEDOM, PENNSYLVANIA.

WRENCH.

1,311,724.

Specification of Letters Patent. Patented July 29, 1919.

Application filed June 29, 1918. Serial No. 242,651.

To all whom it may concern:

Be it known that I, SAMUEL K. SWEITZER, a citizen of the United States of America, residing at New Freedom, in the county of 5 York and State of Pennsylvania, have invented new and useful Improvements in Wrenches, of which the following is a specification.

The purpose of the invention is to provide a wrench of the monkey wrench form in which one jaw is permitted to move away from the other jaw at the movement of the handle in one direction, the movement of the handle in the other direction, however, serving to lock the movable jaw so that relative movement between the two is prevented. Such a construction as this provides for the engagement with a nut or the head of a bolt when the wrench is moved in one direction, but provides for the release of the nut or bolt head by the jaws when the wrench is moved in the opposite direction. Thus there is obtained all of the advantages of a ratchet, with the additional advantage 25 that the jaws are assured of firmly clamping the nut or bolt head when the wrench is being used to move the nut or bolt head in the desired direction.

A further purpose of the invention rests 30 in the provision of a device of this character in which the construction is comparatively simple, the parts for obtaining the desired results few and the cost of manufacture low.

35 Other and further purposes appear in the following description wherein the invention is set forth in detail.

To the exact construction in which it is shown and described, the invention is not 40 to be restricted. The right is reserved to make such changes or alterations as the actual reduction to practice may suggest, in so far as such changes or alterations are compatible with the spirit of the annexed 45 claims.

The same numerals of reference designate the same parts throughout the several figures of the drawings, wherein:

Figure 1 is a view in side elevation of the 50 improved wrench.

Fig. 2 is an edge elevation.

Fig. 3 is a section on the line 3—3 of Fig. 1.

Fig. 4 is a section on the line 4—4 of 55 Fig. 2.

Fig. 5 is a perspective view of the movable jaw.

Fig. 6 is a section on the line 6—6 of Fig. 4.

Fig. 7 is a section on the line 7—7 of Fig. 4.

As illustrated, the invention comprises a hollow body member 1 permanently closed on one side and closed on the other side by the movable plate 2, the body member 65 simulating a rectangular parallelepiped in shape. At a specified distance from either edge wall, the body member 1 is formed with two longitudinal partition members 3 and 3^a which define guide-ways 4 and 5 adjacent either edge of the body member. These guide-ways are square in cross-section for a portion of their length and round for the remainder of their length. The guide-way 5 receives for sliding engagement therein 75 the leg 6 of the stationary jaw 7, the latter and its leg 6 together forming an L-shaped member, as shown. The leg 6 of the jaw member 7 is square in cross-section, so that it may be precluded from angular movement 80 with respect to the body member 1. From a specified point in its length, however, to its free end, the leg 6 is formed with the reduced threaded portion 8 and on this threaded portion 8 the knurled or milled nut 9. 85 is carried. The latter, however, sits in a recess 10 cut in the body portion 1 from that edge adjacent which the guide-way 5 is formed and this recess 10 extends across the guide-way 5, thus making it possible for the 90 nut 10, when engaged with the threaded portion 8 to be secured against any other than rotary movement and rotary movement imparted to the nut will obviously effect longitudinal movement of the threaded 95 portion 8 and the leg 6 with respect to the body portion 1. This for the evident purpose of providing an adjustable means for the jaw 7.

The guide-way 5 is formed so as to be 100 open at both the top and bottom ends of the body portion 1, but the latter is so formed that the guide-way 4 will be closed at the bottom.

In this guide-way 4 there is carried a movable T-shaped jaw element which comprises 105 the jaw proper 11 formed with a leg 12 square in cross-section so that it may slidably engage in the guide-way 4 but be secured against angular movement therein, 110

The leg 12 terminates in a reduced portion 14 circular in cross-section and this latter is surrounded by a spiral spring 15 whose one end bears against the bottom of the 5 guide-way 4 and whose other end bears upon the shoulder formed at the juncture of the leg 12 with its reduced portion 14. Obviously the jaw may be moved in one direction by the action of the spring 15 and 10 in the other direction by the application of a force in opposition to the spring 15. To limit these two movements to prescribed points, slots 16 and 17 are formed in the side wall of the body portion 1 and in the 15 plate 17 respectively, these slots being in alignment so that they may receive the pin 18 inserted transversely through the leg 12 and projecting laterally from either side thereof, the lateral projecting ends of the pin 20 abutting the tops and the bottoms of the aforesaid slots to limit in the jaw 11 the movements above referred to.

The partition members 3^a and 3 together with the side wall of the body portion 1 and 25 the plate 2 define a compartment 19 which is closed at the upper end but which is open at the bottom end of the body portion. This compartment 19 houses devices co-operatively related to the movable jaw 11. The 30 leg 12 of the latter jaw is recessed at the side facing the compartment 19, this recessed portion providing a diagonally disposed side 20. The wall of the partition 3^a is omitted in the vicinity of this diagonally disposed side 20 thus placing in communication the guide-way 4 and the compartment 19.

Pivotedly mounted on a pin 21 set in the side wall of the body portion 1 and engaged 40 by the plate 17, there is a toothed sector 22 provided with an arm 22^a designed to lie against the diagonally disposed side 20. This toothed sector 22 meshes with a similar sector 23 pivotally mounted on a pin 29' and 45 having a depending arm 24 of gradually increasing width which becomes greatest at the free end, thus providing an inclined edge surface 25 against which the nose 26 of the handle 27 may engage. The handle 27 50 is pivotally mounted on a stud 28 while a flat spring 29 attached to the partition member 3 bears on the handle and tends to keep its nose 26 firmly engaged with the inclined edge 25 of the arm 24. Obviously this serves 55 to keep the arm 22^a in engagement with the inclined side 20 of the leg 12, thus preventing the jaw 11 from being moved away from the jaw 7 on the application of a force upon the former. When the jaw 11 stands in 60 such a position relative to the body member 1 that the pin 18 engages the upper ends of the slots 16 and 17, the positions of the arms 22^a and 24 are such that the nose 26 of the handle 27 bears against the inclined edge 25 65 at a point slightly above an imaginary line.

drawn through the center of the stud 28 in a plane parallel to the upper and lower edges of the body portion 1.

In the use of the device, when the movable jaw 7 is in the position just stated, the 70 stationary jaw 7 is adjusted relative to this movable jaw so as to suit the nut or bolt to be operated upon. The wrench is then so positioned on the nut or bolt that when the latter is turned in the desired direction, the 75 pressure exerted on the handle 27 for movement of the nut in this desired direction will co-operate with the spring 29 to keep the nose and with it the arms 24 and 22^a in such positions as to preclude any downward 80 movement of the jaw 11 or any movement thereof relative to the jaw 7. When it is desired, after having moved the nut and the wrench through a specified angular distance, to secure a new hold on the nut, the pressure 85 exerted on the handle 27 is, of course, reversed, with the result that the nose 26 is moved out of firm engagement with the inclined edge 25, when the wrench as a whole may be moved in a reversed direction as respects the movement being imparted to the nut, the movable jaw 11 moving away from the jaw 7 to effect passing around the corners of the nut. Since the nose 26 is moved out of firm engagement with the inclined 95 edge 25, this movement of the jaw 11 is possible, since the pressure exerted on top of the jaw is transferred in turn to the arm 22^a and from the latter through the toothed sectors 22 and 23 to the arm 24 which later of 100 course is moved toward the nose 26.

From the accompanying drawings and the foregoing description, it is believed that a clear enough understanding of the invention is to be had, and a further description 105 is, therefore, omitted.

The invention having been described, what is claimed as new and useful is:

1. A wrench of the class described comprising a body portion formed with a guide-way, a jaw carried by the body portion and held normally stationary relative thereto, a movable jaw co-operating with the first said jaw, the said movable jaw being formed with a leg slidingly engaging the said guide-way, intermeshing toothed sectors pivotally mounted in the body portion, the one being formed with an arm, the leg of the movable jaw being recessed to provide an inclined edge with which the said arm may engage, the other of the toothed sectors being formed with an arm of increased width at its free end to provide an inclined side edge, a handle pivotally mounted in the body portion and having a nose engaging the said inclined edge of the last said arm, and a spring carried by the body portion and bearing upon the handle to keep the nose thereof normally in such engagement. 125

2. A wrench of the class described com- 130

prising a body portion, a relatively stationary jaw carried thereby, a movable jaw carried by the body portion and coacting with the first named jaw, the said movable jaw being formed with a leg slidably engaging the body portion, a handle pivotally connected with the body portion, and a pair of intermeshing tooth sectors carried in the body portion, the one being operatively con-

nected with the handle and the other with 10 the movable jaw, whereby the exercise of pressure of the handle in one direction may serve to lock the jaw while pressure on the handle in a reverse direction releases the jaw for the purpose specified. 15

In testimony whereof he affixes his signature.

SAMUEL K. SWEITZER.
